CLAIR C. WOLVERTON, OF INDIANAPOLIS, INDIANA.

BUCKLE.

Application filed November 20, 1926. Serial No. 149,749.

This invention relates to a buckle construction particularly suitable for a hopple.

The chief object of the invention is to provide a buckle for a hopple construction which is relatively simple in character and which will permit of relatively quick adjustment of the hopple and which also is so arranged that it will prevent pivotal movement in the hopple from ring to ring thereof.

The full nature of the invention will be understood from the accompanying drawings and the following description and claims:

15 In the drawings Fig. 1 is a top plan view of a pair of rings of a hopple connected together by the buckle. Fig. 2 is a side elevation thereof. Fig. 3 is an enlarged side elevation of preferred form of buckle. Fig. 4 20 is a top plan view thereof.

In horse racing to prevent the horse from breaking from a pacing gait, a hopple construction is generally utilized. The desirable features to be obtained in a hopple construction are minimum interference with the horse when pacing and sufficient interference when otherwise traveling to remind the horse that the other gait is not a pace. The most satisfactory hopple heretofore employed has 25 consisted of a pair of rings in alignment with each other for the front and rear legs, the same being connected together to reach straps which are laced together, the lacing passing through a plurality of registering 30 holes in each of the parallel positioned reach straps. The aforesaid construction has the advantage that no pivot is provided between the rings, whereby the rings would pivot 35 relative to the plane of alignment, it being understood, of course, that the rings do have slight but sufficient bending movement by 40 reason of the flexibility of the straps. However, with a laced construction, to readily adjust the same requires that the entire lacing be removed and then replaced in the 45 registering openings after the parallel reach straps have been shifted relatively of each other.

The present invention permits the construction of a hopple having substantially no pivotal movement other than that found in the laced hopple construction and which will permit ready and almost instantaneous adjustment. In fact, the adjustment may be

made while the hopple is positioned on the 55 horse. The simplified construction consists of a pair of tongues or extensions of one portion of the reach which is associated with a multiple buckle, the present invention, the same being arranged for non-pivotal movement but permitting sliding movement of 60 said tongues.

In the drawings 10 indicates the ring portions, 11 the carrier portions, and 12 the reach straps which are divided from the encircling loop 13, forming the branches or tongues 14, said branches or tongues having a plurality of registering apertures 15. The other ring 10 forms a loop 16 and said loop 16 passes through an opening 17 in the plate 18 of the multiple buckle. The plate 18 has a single extension 19 or equivalent means, which is adapted to lie parallel to the straps forming the ring 10 adjacent the pivot or loop 16, and thus prevents relative pivotal movement of the buckle and the loop 16. A pair of rectangular openings 20 are provided by the connecting portion 21 or opposite end of the buckle and the rectangular open framework 22 positioned in a plane substantially transverse to the plane of the body portion of the buckle. The body portion 21 of the buckle from the rectangular frame 22 to substantially the opening 17, is provided with an elongated slot 23. Slidably 70 mounted in said slot is a pin 24 having the pointed extensions 25 extending oppositely of each other and in alignment with each other and the collar retaining portions 26, thereby preventing transverse movement of 75 the buckle pin in the elongated slot 23.

Each of the reach strap tongue portions 14 is positioned in one of the rectangular openings 20 of the framework 22 and the extended portion lies parallel to the body portion of the buckle when said buckle separates said tongues. When the pin 24 is moved to the end of the slot adjacent opening 17 the tongues 14 can be spread apart and the pointed ends 25 of the pin 24 inserted in 100 the desired pair of registering apertures 15. Following this insertion the buckle construction, or the pin and tongues, are moved, and relatively of each other, so that the pin is positioned as shown in Figs. 1 and 2, that is, adjacent the frame portion 22. The free ends of the tongues then are positioned in the loops 27 carried by ring 10 including the 105

buckle receiving loop 16, while a slidably supported encircling loop 28 carried by the reach portion 12 is slid along said reach straps until it substantially abuts the framework 22.

The resultant construction is one wherein from ring to ring there is no pivot. The only possible pivot by reason of loop 16 being a non-pivotal arrangement since the 10 tongue 19 is provided to prevent such pivotal movement. There is no possibility of the connection becoming disconnected since the several loops 27 and 28 positively lock the relatively movable parts in the adjusted 15 position.

When it is desired to adjust the reach the tongues 14 are freed from the loops 27 and loop 28 is retracted. The buckle is then moved towards the other ring until the pin 20 24 is positioned at the far end of the slot 23, that is, nearest the tongue 19. When in this position the several tongues 14 are moved outwardly to free them from projecting ends 25 of the pin 24. The entire mechanism 25 is then adjusted so that the pins 25 will be repositioned in the selected pair of registering openings 15 following which the parts are repositioned as heretofore described.

From the foregoing it will be apparent 30 that the hopple construction includes substantially no pivotal arrangements and, therefore, will have rectilinear movement only and will be readily adjustable.

The invention claimed is:

35 1. A multiple buckle, comprising a pair of transversely positioned sockets, a connecting portion therebetween adapted to divide one of said sockets into a multiple socket, and means slidably mounted on said connecting

portion and adapted to simultaneously co- 40 operate with each of the divided sockets.

2. A device as defined by claim 1, characterized by said slidably cooperating means constituting a pin having portions projecting oppositely and substantially transverse 45 to the connecting portion, the latter including an elongated slot for receiving the pin.

3. A device as defined by claim 1, characterized by the addition of a non-pivot forming projection adjacent the non-divided 50 socket.

4. A multiple buckle including a pair of rectangular sockets positioned transversely of each other, an elongated longitudinally extending connecting portion uniting the 55 same in rigid relation and a fixed distance apart, and means slidably mounted on the connecting portion independent of the longitudinal socket and cooperating with the transverse socket. 60

5. A multiple buckle including a pair of rectangular sockets positioned transversely of each other, an elongated longitudinally extending connecting portion uniting the same in rigid relation and a fixed distance 65 apart, means slidably mounted thereon for cooperation with the socket positioned transversely of the sliding movement, and an extension upon the other or non-cooperating socket for rigid anchorage of the buckle in 70 predetermined position.

6. A device as defined by claim 5 characterized by said buckle-positioning extension extending oppositely from said socket and in alignment with said connection portion. 75

In witness whereof, I have hereunto affixed my signature.

CLAIR C. WOLVERTON.
